US00D800097S

(12) **United States Design Patent** (10) **Patent No.:** **US D800,097 S**
Chen (45) **Date of Patent:** **** Oct. 17, 2017**

(54) **WIRELESS EARPHONE**

(71) Applicant: **Dongguan City Hele Electronic Co., Ltd.**, Guangdong Province (CN)

(72) Inventor: **Shukang Chen**, Dongguan (CN)

(73) Assignee: **DONGGUAN CITY HELE ELECTRONIC CO., LTD.**, Guangdong Province (CN)

(**) Term: **15 Years**

(21) Appl. No.: **29/570,975**

(22) Filed: **Jul. 13, 2016**

(30) **Foreign Application Priority Data**

May 5, 2016 (CN) 2016 3 0160575
